CLAIM

The ornamental design for a stackable three compartment bulk food display module, as shown and described.

DESCRIPTION

FIG. 1 is a perspective view of a stackable three compartment bulk food showing my new design;

FIG. 2 is a front elevational view thereof;

FIG. 3 is a top plan view thereof;

FIG. 4 is a left side elevational view the right side being a mirror image thereof;

FIG. 5 is a bottom plan view thereof; and

FIG. 6 is a front elevational view showing the module as it would appear in an environmental setting. The broken line showing of portions of other modules is for illustrative purposes only and forms no part of the claimed design.

FIG. 1

FIG. 4

FIG. 2

FIG. 5

FIG. 3

FIG 6
